UNITED STATES PATENT OFFICE.

HARRY M. MOSES, OF RICHMOND, VIRGINIA, ASSIGNOR TO THE H. M. MOSES COMPANY, OF SAME PLACE.

DESIGN FOR A SPOON.

SPECIFICATION forming part of Design No. 21,987, dated November 15, 1892.

Application filed May 14, 1892. Serial No. 433,061. Term of patent 7 years.

To all whom it may concern:

Be it known that I, HARRY M. MOSES, of Richmond, in the county of Henrico and State of Virginia, have invented and produced a new and original Design for Spoons, of which the following is a specification, reference being had to the accompanying drawing, forming a part thereof.

A spoon embodying my present design has a bowl of ordinary contour, and the handle portion presents the appearance of a Corinthian column with an enlarged base B united to the bowl. The base B is in relief and presents the appearance of a rectangular pedestal, its major and lower portion being located within the line of the periphery of the bowl, leaving clear spaces on each side, conforming to the curvature of the bowl and giving a highly-artistic and symmetrical effect. Above the base the plain shaft or column C is indented or marked to present the appearance of successive blocks or cylindrical sections

in imitation of a column built of stone, and at the top of the shaft is the usual cap-piece D, ornamented in accordance with the Corinthian style. Surmounting the cap-piece, which forms its pedestal, is a figure E of a soldier carrying a gun and in the attitude of rest, with one hand raised to shade his eyes, the gun being held in the other hand at a point near the muzzle, with its stock resting on the pedestal or ground. The soldier is further represented as wearing a slouch hat and with his blanket slung over one shoulder and his canteen and other paraphernalia slung over the other shoulder.

What I claim is—

The design for a spoon, as herein shown and described.

HARRY M. MOSES.
